UNITED STATES PATENT OFFICE

GEORGE J. MEUER, OF MILWAUKEE, WISCONSIN, ASSIGNOR TO CUTLER-HAMMER, INC.,
OF MILWAUKEE, WISCONSIN, A CORPORATION OF DELAWARE

DESIGN FOR A ROTARY FEED-THROUGH SNAP SWITCH

Application filed December 1, 1930. Serial No. 37,859. Term of patent 14 years.

To all whom it may concern:

Be it known that I, GEORGE J. MEUER, a citizen of the United States, residing at Milwaukee, in the county of Milwaukee and State of Wisconsin, have invented a new, original, and ornamental Design for a Rotary Feed-Through Snap Switch, of which the following is a specification, reference being had to the accompanying drawing, forming part thereof.

Figure 1 is a front elevational view of a rotary feed-through snap switch showing my new design.

Fig. 2 is a rear elevational view of the switch shown in Fig. 1.

Fig. 3 is a perspective view of said switch.

I claim:

The ornamental design for a rotary feed-through snap switch, substantially as shown.

GEORGE J. MEUER.
